No. 835,629.

PATENTED NOV. 13, 1906.

R. J. MINER.
GASEOUS FUEL BURNER.

APPLICATION FILED MAR. 23, 1904. RENEWED MAY 18, 1906.

UNITED STATES PATENT OFFICE.

ROBERT J. MINER, OF GREENWICH, CONNECTICUT, ASSIGNOR TO KERO-
SENE POWER COMPANY, OF NEW YORK, A COPARTNERSHIP COMPOSED
OF HIMSELF, HUBERT D. BRENNAN, DANIEL G. BRENNAN, AND GUSTAV
MASSA.

GASEOUS-FUEL BURNER.

No. 835,629.

Specification of Letters Patent.

Patented Nov. 13, 1906.

Application filed March 23, 1904. Renewed May 18, 1906. Serial No. 317,421.

To all whom it may concern:

Be it known that I, ROBERT J. MINER, residing at Greenwich, in the county of Fairfield and State of Connecticut, have invented 5 a new and Improved Gaseous-Fuel Burner, of which the following is a specification.

My present invention, which generally relates to improvements in that class of gaseous-fuel burners especially designed for vaporizing and burning kerosene-oil for generating steam for motor-vehicles, &c., has for its object to provide an improved burner of the kind stated in which is included a simple and effective means for continuing the vaporization of the volatile fluid for keeping up the steam during the time the main burner is cut out—*i. e.*, when the motor is at a standstill or traveling under momentum.

My present invention comprehends an improved construction of burner in which a main vapor-feed for supplying the main burner-tubes and a supplemental feed for supplying the auxiliary torch-tubes of the burners are provided and which are both fed 25 from a single fuel-supplying pipe and in which is also included a means for cutting off the fuel-feed to the main burner without affecting the feed of the fuel to the torch or supplemental burner-tubes.

In its more complete nature my present invention embodies an improved construction of burner comprising a main gas-distributing chamber having a series of main ejecting-tubes, a supplemental gas-chamber having a series of supplemental or torch tubes that coact with the main tubes and a fuel-feed pipe common to both gas-chambers, and a valve mechanism automatically operative by the varying steam-pressure in the boiler 35 for cutting off the gas-supply to the gas-chamber, with which the main burner-tubes connect, without disturbing the gas-feed to the supplemental or torch tubes.

In its more subordinate features my invention consists in certain details of construction and combination of parts, all of which will be hereinafter fully explained, specifically pointed out in the appended claims, and illustrated in the accompanying drawings, in 45 which—

Figure 1 is a view of my invention, partly in side elevation and partly in longitudinal section. Fig. 2 is a top plan view thereof.

Fig. 3 is an enlarged view of the automatically-actuated device that controls the cut-off 55 valves.

In the practical application of my invention I provide a burner-body in the nature of a hollow casing 1, which constitutes the main gas-collecting chamber, hereinafter referred to, and which consists of a base-plate 1^a, upon which the shell or casing portion is bolted, as shown.

2 designates what is hereinafter termed a "supplemental" gas-chamber, which is in 65 the nature of a box-like frame, that is preferably bolted on the under side of the base-plate 1^a, but may be connected thereto in any approved manner.

3 designates a mixing-tube, which in my present construction of burner is arranged to freely discharge into the main chamber or casing 1 at a point near its upper end, and it is also provided with a small outlet 3^a, that communicates with the supplemental chamber 75 2, as clearly shown in the drawings.

In my present form of burner I provide a series of compound burner-tubes that extend under and are arranged to discharge directly against the vaporizer or generating-tube 80 presently referred to, and the said compound burner-tubes consist of a main tube that burns only when the fuel-feed is discharging into the main gas-collecting chamber and a torch-tube that burns all the time that the 85 burner is in use, and the said compound burners each consists of an air-tube 4, detachably mounted in the base-plate 2^a, that forms the bottom of the supplemental chamber 2 and which passes up through the main 90 gas-collecting chamber 1 to project above the top thereof, as clearly shown in the drawings.

5 designates a tube that surrounds the air-tube 4 and which communicates at the lower end with the supplemental chamber 2. The 95 tube 5 is fixedly secured to the base-plate 1^a of the main casing and has its upper end projected above the top of the said casing and in close relation to the upper end of the air-tube 4, as shown.

6 designates openings in the top plate 1^c of the main gas chamber or casing 1, through which the tubes 4 and 5 pass and which form the gas-outlets of the burners.

So far as described it will be observed that 105 each burner consists of a gas-tube 5, which

constitutes the torch hereinafter referred to, an air-tube 4, located within the tube 5, and a short tube 6^a, that forms a continuation of the openings 6, that communicates with the main gas-chamber and which forms the main burner hereinafter referred to. Under ordinary conditions—that is, when gas is being fed to both the main gas chamber or casing 1 of the supplemental chamber 2—a fierce fire is disseminated from the main and torch tubes that constitute the complete compound burners; but when the gas fed to the main chamber or casing 1 is cut off in the manner presently explained the compound burners will receive fuel from the supplemental chamber 2 only, and the several burners then act as mere torches to eject a moderate heat against the generator.

To provide for cutting out the main burners by shutting off the supply of the volatile fluid to the main chamber or casing 1 without affecting the feed of the volatile fluid to the torch-burners 5, I provide a suitable valve mechanism, which in the most complete form of my invention is arranged to be automatically shifted by the varying pressure of the steam within the boiler. In the drawings I have shown one form of mechanism for accomplishing the automatic shifting of the valve; but it will be understood that the said valve-shifting mechanism may be readily modified or varied to suit the conditions that may be required without departing from the scope of my invention and the appended claims.

In the drawings, I have shown a flat valve 4 fulcrumed at 4^b on the base-plate 1^a in such manner that when at its closed position it rests over and closes the discharge-mouth of the mixing-tube 3, and the said valve at its hinged end has a crank 4^a, which connects with a shifting-rod 7, that extends beyond the casing or main chamber 1, so as to admit of its being conveniently manipulated exteriorly of the said main chamber or casing 1.

When it is desired to obtain the full or maximum efficiency of my improved burner, the valve 4 is opened by pulling on the rod 7 in the direction indicated by the arrow 10, it being manifest that the shifting of the said rod in the opposite direction serves to again close the said valve.

In the preferred or complete form of my invention the rod 7 extends within a casing 8 and terminates in a head 7^a, and the said rod is held drawn to its outer position to maintain the valve open through the medium of a spring 9. Within the casing 8 is mounted a diaphragm 11, and the said casing 9 connects with a pipe connection 12, that leads to the steam-space of the boiler. The parts just described in practice are so arranged that when the pressure in the boiler passes beyond the predetermined degree the steam-pressure on the diaphragm forces the shifting-rod

7 out against the tension of its spring and closes the valve 4, and thereby cuts off the supply of the gaseous fuel to the main feed-outlets 6 of the burners without interfering with the feed of the fuel to the torch devices that constitute a part of the said burners, it being understood that when the pressure in the boiler falls below the predetermined degree the spring 9 again shoves the member 7 outward, and thereby opens the valve 4 and allows the fuel to again feed into the chamber 1 and to the main burner-outlets.

It is understood that in my present type of burner the supplemental gas-collecting chamber is of a size sufficient to disseminate the moderate amount of fuel-feed discharged therein through the small outlet in the mixing-tube to the several compound burners that act as torches for keeping up the vaporization of the oil within the generator. In addition to the compound burners before explained it is my practice to provide a number of additional burner-tubes *x x*, that are fed from the main gas-collecting chamber and which comprise the air-tubes 40 and gas-tubes 50, arranged as shown. The burner-tubes *x x*, it is understood, are also cut out when the supply to the main chamber is cut off.

From the foregoing description, taken in connection with the accompanying drawings, it is thought that the complete operation and advantages of my improved burner will be readily understood by those skilled in the art to which it appertains.

When the automatic cuts down, it operates the valve to close the main burner entirely, but allows the torches to burn, as before.

It will be seen that when the main fire is on there is a double row of tubes which burn under the generator, and when the main fire is cut off by the automatic there is but a single row of tubes—the torch-tubes—under the generator burning, which torch-tubes, it should be stated, burn all the time, while the main burner is wholly or partly cut off, as may be desired, and when the steam-pressure causes the automatic to act.

By reason of the peculiar construction of my burner the torch is noiseless and an even distribution of heat goes along the entire length of the generator, which reduces carbonization to a minimum. It will not blow out, as is usually the case with an ordinary torch, as my improved torch forms a co-operating part of the complete burner.

In my construction of burner any well-known arrangement of vaporizing-tube may be provided—as, for example, such as is shown in the drawings, in which the tube 15 is shown extending horizontally over the burner-tubes directly within the greatest heat zone of the said tubes and provided with a pendent feed-offtake 15^a, in the lower end of which is mounted the usual type of ejector

or needle-valve 16, which distributes into the mixing-tube, as shown.

By reason of having the supplemental or small outlet in the mixing-tube that feeds to the torch-tubes adjacent the main discharge of the pipe 3 the said small outlet will be kept clear of deposits or from choking up by the fierce draft of the fuel-feed through the main discharge when the valve is opened.

Having thus described my invention, what I claim, and desire to secure by Letters Patent, is—

1. A gaseous-fuel burner, comprising, a main fuel-receiving chamber and a supplemental fuel-receiving chamber, a series of burners one of which consists of an air-tube, a main tube that communicates with the main fuel-receiving chamber, a torch-tube that communicates with the supplemental fuel-chamber, a vaporizer mounted in the heat zone of the burners, a mixing-tube that communicates with the main and supplemental fuel-receiving chambers, and a valve that communicates with the mixing-tube adapted when closed to cut out the said mixing-tube or feed from the main receiving fuel-chamber, for the purposes specified.

2. The combination of a series of main burner-tubes, a series of torch-tubes that are located within and coöperate with the main burner-tubes, a vaporizer in the heat zone of the two sets of burner-tubes, a means for supplying fuel to both burner-tubes, said means including a valve for cutting out the flow of the fuel to the main burner-tubes, and devices for shifting the said valve that are controlled by the varying steam-pressure in the

boiler steamed up by the burners, as described.

3. A burner of the character described, comprising a main fuel-collecting chamber, a supplemental fuel-collecting chamber, a series of air-pipes that extend through both chambers, torch-tubes that surround the said pipes, communicate with the supplemental fuel-chamber and project through the other chamber, a second set of tubes that surround the upper ends of the torch-tubes and which communicate with the main fuel-collecting chamber, a vaporizer within the heat zone of the burner-tubes, a mixing-tube connected therewith and having two separate discharges, one of which empties into the main fuel-chamber and the other into the supplemental fuel-chamber, a valve for cutting off the mixing-tube discharge into the main chamber and a means operable from the outside of the chamber for shifting the valve.

4. The combination of a burner, a vaporizer in the heat zone thereof, said burner including a series of compound burner-tubes arranged to discharge directly against the vaporizer, a single fuel-feed to the said compound burner-tubes, said compound burner-tubes comprising a main and a torch-ejecting tube, means for controlling the fuel-feed whereby to cut off the feed to the main ejecting-tube without cutting out the torch-ejecting tube.

ROBERT J. MINER.
